United States Patent Office.

W. A. C. OAKS, OF READING, PENNSYLVANIA, ASSIGNOR TO HARBSTER, BROTHERS AND COMPANY, OF SAME PLACE.

Letters Patent No. 74,412, dated February 11, 1868.

IMPROVED WINDOW-SHADE FIXTURE.

The Schedule referred to in these Letters Patent and making part of the same.

TO ALL WHOM IT MAY CONCERN:

Be it known that I, W. A. C. OAKS, of Reading, in the county of Berks, and State of Pennsylvania, have invented a new and useful Improvement in Window-Shade Fixtures; and I do hereby declare that the following is a full, clear, and exact description of the same, reference being had to the accompanying drawings, making a portion of this specification, in which—

Figure 1 is a front view of a shade-fixture constructed according to my invention.

Figure 2 is a longitudinal transverse section of the same.

Similar letters of reference indicate corresponding parts in both figures.

This invention relates to that variety of devices employed to retain the cords of window-shades in position, and its object is to provide an efficient fixture for the purpose named, which will be more simple in construction, and consequently capable of being manufactured at a much less cost than those hitherto in use.

The invention consists in the combination of a recessed guide-plate or frame, a tension-slide, and a flat zigzag spring, whereby the desired object is secured.

To enable others to understand the construction and operation of my invention, I will proceed to describe it with reference to the drawings.

A represents the guide-plate, which receives and holds the other or working parts of the fixture, and which is designed to be secured to the window-frame, by screws passing through lugs *a*, of appropriate form, provided upon the said guide-plate, as shown more fully in fig. 1. Formed in the back or rear side of the guide-plate *A* is a longitudinal recess, *b*, preferably of nearly or quite rectangular shape in its transverse section, and which has placed in its innermost portion, as shown more clearly in fig. 2, a spring, *c*, formed of a strip of any suitable sheet metal, bent into zigzag shape, as indicated in dotted outline in fig. 1, and which, having two flat sides, is enabled to play within the narrow space allotted to it. Situated behind the spring just described, and in the outer or back portion of the recess *b* of the guide-plate, is the tension-slide *B*, the main length of which is of flattened form, and at the lower end of which is an inwardly-extending spur or shoulder, *b*, against which bears the lower end of the spring *c*, the upper end of the said spring resting against the top *a'* of the guide-plate, the said top *a'* being cut away at its back part to permit the slide *B* to extend past the same, as more plainly represented in fig. 2. The said slide is furnished, at its upper extremity, with a hook, *d*, or like means, whereby the shade-cord may be attached thereto, as hereinafter further set forth, and which extends forward over the guide-plate, and to which the shade-cord may be attached in the usual manner, as indicated in red outline in the fig. 2, just mentioned. When the fixture is secured to the window-frame, as hereinbefore explained, the spring *c* and the slide *B* are retained in proper position by the surface of such window-frame closing the back or rear side of the recess, in which the said parts are placed. The spring *c*, by pressing downward the hooked slide *B*, of course draws upon the cord attached, as hereinbefore mentioned, to the hook *d* thereof, and retains the same at the required degree of tension.

From the small number of parts involved in the construction of the fixture, and the convenience with which they may be fitted together, the said fixture may be manufactured at a cost much less than that of those hitherto devised, without at all detracting from the efficient operation of the same when in use.

What I claim as my invention, and desire to secure by Letters Patent, is—

The combination of the recessed guide-plate *A*, the zigzag spring *c*, and the slide *B*, substantially as and for the purpose specified.

W. A. C. OAKS.
